United States Patent Office

Des. 189,253
Patented Nov. 15, 1960

189,253

PLATE OR SIMILAR ARTICLE

John H. Reiser, Downey, Calif., assignor to Wallace
China Co., Ltd., Los Angeles, Calif., a corporation of California

Filed Sept. 21, 1959, Ser. No. 57,619

Term of patent 14 years

(Cl. D44—15)

The figure is a plan view of a plate of conventional configuration showing my new design. The section of motif shown is continued around the entire circumference of the plate.

I claim:

The ornamental design for a plate or similar article, substantially as shown and described.
